(57) **CLAIM**

The ornamental design for the external surface configuration for the front panel of a stove, as shown and described.

DESCRIPTION

FIG. 1 is a front perspective view of an external surface configuration for the front panel of a stove, showing our new design;

FIG. 2 is a front perspective view thereof with a drawer thereof pulled partially out;

FIG. 3 is a front elevation view thereof;

FIG. 4 is a right side elevation view thereof, the left side being a mirror image thereof; and,

FIG. 5 is a top plan view thereof.

The details shown in broken lines in FIGS. 1-5, and the undisclosed rear and bottom views form no part of the claimed design.
